UNITED STATES PATENT OFFICE

2,481,779

ROTATABLE GAME BOARD

Bernhart M. Peterson, Minneapolis, Minn.

Application September 4, 1947; Serial No. 772,033

2 Claims. (Cl. 273-136)

1

My present invention relates to games of the type wherein a plurality of game pieces, otherwise known as men, are moved from one portion of a board to a different portion thereof, as in the game of checkers or the like.

An important object of my invention is the provision of a game having a pair of spaced game boards and a connecting bridge element over which game pieces may be moved from one board to the other along a predetermined path.

Another highly important object of my invention is the provision of a game as set forth, wherein the spaced game boards have paths thereon, some of which are extended to form entrance and exit ways and adapted to be aligned with paths of the connecting bridge element.

Still another important object of my invention is the provision of a game as set forth, in which the game board has paths, some of which are extended to form a plurality of entrance and exit ways, and in which the game boards may be simultaneously rotated to align any one of the entrance and exit ways with the paths on the bridge element.

A still further object of my invention is the provision of means for checking the rotation of the game board when any one of the entrance and exit ways are in alignment with the bridge element.

Other objects and advantages of my invention will become apparent from the following specification, appended claims, and attached drawings.

Referring to the drawings, in which like characters indicate like parts throughout the several views:

Fig. 1 is a view in perspective of my improved game with some parts being broken away and some parts shown in section;

Fig. 2 is a longitudinal sectional view taken substantially on the line 2-2 of Fig. 1.

In the embodiment of my invention shown, the numeral 1 indicates, in its entirety, a frame comprising a box-like base 2 and bearing brackets 3 and 4. A top plate 5 of the base 2 is provided with a laterally-spaced pair of openings 6, each of which overlies one of the brackets 3 and 4. The brackets 3 and 4 are secured within the base 2 by means of screws or the like 7.

A pair of vertically-extending shafts 8 and 9 are journaled in the bracket 3 and 4, respectively, and project upwardly through the openings 6 in the top plate 5. At their opposite ends, the shafts 8 and 9 are equipped with rigidly mounted flanges 10 and 11, respectively. The flanges 10 and 11 are disposed upon their respective shafts

2

to closely overlie the top plate 5 and entirely cover the openings 6 thereof.

Rigidly secured to the flanges 10 and 11, respectively, is a pair of game boards in the nature of flat discs 12 and 13. These discs 12 and 13 are preferably of equal diameter and have their top surfaces on the same horizontal level. The diameter of the discs 12 and 13 and the lateral spacing thereof is such that a bridge element 14 may be interposed therebetween. The bridge element 14 is rigidly mounted to the top plate 5 and is provided with spaced parallel sides and concave ends which closely correspond to the curvature of the adjacent discs 12 and 13. The top surface of the bridge element is on a common level with the discs 12 and 13, and sufficient clearance is maintained between the concave ends of the bridge element and the discs so that the discs may rotate freely with respect to the bridge element 14.

A pair of bevel gears 15 is mounted fast, one each on the shafts 8 and 9 within the base 2, and is connected for simultaneous rotation by having meshing engagement, one each with one of a pair of bevel pinions 16 fast on the opposite ends of a laterally-extended shaft 17. The shaft 17 is journaled adjacent its end in the brackets 3 and 4. It will be seen, particularly by reference to Fig. 2, that rotation of one of the discs 12 or 13 will be transmitted through the gears 15, pinions 16, and shaft 17, to the other thereof. By means of this arrangement, rotation of one of the discs 12 or 13 will cause rotation of the other thereof in a reverse direction.

I provide means for checking rotation of the discs 12 and 13 at predetermined positions, in the nature of a cam 18 secured to the shaft 9 by means of a set screw or the like 19. The cam 18 is provided with a plurality of relatively flat surfaces 20 which are adapted to be frictionally engaged by the free end of a leaf spring 21. Spring 21 is fastened to and held in cam-engaging position by a mounting block 22, secured to the base 2.

The game boards or discs 12 and 13 are each laid out to provide a plurality of intersecting paths over which game pieces are adapted to be moved. The game pieces, not shown, may be of several types such as pegs or marbles adapted to be moved in paths made up of holes or concavities in the game boards; but preferably and as shown, I provide paths imprinted on the flat upper surfaces of the discs 12 and 13 for the use of ordinary checker pieces or the like. The paths are indicated by the numeral 23 and intersect at substantially 90°. As shown, some of the paths ter-

minate at the periphery of the discs 12 and 13 to form entrance and exit ways 24. The bridge element 14 is similarly laid out to provide a plurality of paths 25, which terminate at the opposite concaved ends thereof and form continuations of the paths 23 when the discs 12 and 13 are rotated to bring the entrance and exit ways 24 into alignment therewith.

The flat surfaces 20 of the cam 18 are so arranged, with respect to the entrance and exit ways 24 on the discs 12 and 13 and the spring 21, that one of said surfaces will be in face-to-face engagement with the spring 21 when any one of the entrance or exit ways 24 are aligned with the bridge element 14. Cam 18 and spring 21 thus function as a detent to assure alignment of the paths 24 and 25 in the discs and bridge element, respectively. It will be noted that, when an entrance way 24 on the disc 12 is aligned with the bridge element 14, a corresponding entrance way 14 on the disc 13 is also brought into alignment with the bridge element 14.

The end to be achieved in playing the game is to move all of the game pieces from one of the game boards 12 or 13 to the other thereof through the entrance and exit ways 24 and over the bridge element 14. During the game, different ones of the ways 24 may be brought into alignment with the bridge element 14, so that many combinations of movement of the game pieces are thereby possible. Various methods of playing the game may be used, which it is thought need not be described, inasmuch as the instant invention is concerned only with the structure herein disclosed.

While I have shown and described a preferred embodiment of my invention, it will be understood that the same is capable of modification without departure from the scope of the invention.

What I claim is:

1. In a device of the class described, a frame, a pair of laterally-spaced disc-like game boards

mounted in said frame on spaced axes for simultaneous rotation in a common plane, the upper surfaces of each of said discs being laid out to form a plurality of intersecting paths over which 5 game pieces are adapted to be moved, some of said paths on each of said discs terminating adjacent the periphery of said discs to provide a plurality of circumferentially-spaced entrance and exit ways, a stationary bridge element interposed between said discs, said bridge element being laid out to provide a plurality of paths which terminate at opposite edges thereof adjacent said discs, said paths forming continuations of the paths in said discs when aligned 10 therewith, motion transfer mechanism mounted on said frame and connecting each of said discs for simultaneous rotary movement, and means for checking rotation of said discs when the paths in said entrance ways are aligned with the 15 paths of said bridge.

2. The structure defined in claim 1 in further combination with means for rotating said discs in opposite directions.

BERNHART M. PETERSON.
